(57) **CLAIM**

The ornamental design for a solar lantern, as shown and described.

DESCRIPTION

FIG. 1 is a front perspective view of a solar lantern, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the solar lantern, which form no part of the claimed design. All unshaded areas adjacent to broken lines form no part of the claimed design.
